HEBER R. RIDGLEY, OF MANSFIELD, OHIO.

Letters Patent No. 73,389, dated January 14, 1868.

IMPROVED HARNESS-PAD.

The Schedule referred to in these Letters Patent and making part of the same.

TO ALL WHOM IT MAY CONCERN:

Be it known that I, HEBER R. RIDGLEY, of Mansfield, in the county of Richland, and State of Ohio, have invented a new and improved Iron for Harness-Pads; and I do hereby declare that the following is a full, clear, and exact description thereof, which will enable others skilled in the art to make and use the same, reference being had to the accompanying drawings, forming part of this specification:

This invention relates to a harness-pad and iron as an improved article of manufacture, and it consists of the solid flanged pad-iron, having the crupper-loop cast upon and with it, and the continuous pad, having its upper surface formed of sole-leather, covering and securing the burrs for the terrets and ornamental screws, as will be hereinafter more particularly described.

Figure 1 is a front elevation of my improved pad-iron, partly in section, to show the method of attaching the pad to the iron.

Figure 2 is a cross-section of the same taken in the line $x x$, fig. 1.

Similar letters of reference indicate like parts in the two figures.

In the drawings, m is the pad-iron, to which the exterior straps r and pads d are attached. This iron is cast in one piece, and is provided upon its edges with flanges n , as shown in fig. 2. The portion between the flanges is cast solid, forming a seat, adapted to receive the strap r and the pad d upon its upper and lower surfaces respectively. Upon the rear portion of the pad-iron the crupper-loop is cast, being formed of the same metal, and cast with said iron. I am aware that crupper-loops have heretofore been attached to pad-irons by means of bolts and nuts; but this method of attachment greatly enhanced the cost of manufacture, and at the same time rendered it less secure when in use. These loops have also been formed of wrought iron, and brazed into the cast metal, but any undue strain upon the crupper-strap had the effect of drawing the loop from its socket. By my construction the loop is rendered secure, and at the same time the use of nuts and bolts avoided, thus reducing materially the cost of manufacture, and presenting a neater and more complete pad-iron. The upper side, m' , of the pad d , is formed of a thick piece of sole-leather, and fits between the flanges n . The burrs e , for the ends of the ornamental screws p , terrets B , and hook A , are placed within the pad, beneath the upper side, m' , to which they are secured. By this construction the burrs are prevented from coming in contact with the pad-iron, and are less liable to become worn or loosened, while the thickness of the leather prevents them from being torn from the pad. The terrets are inserted in the iron and pad in the usual manner, the bases of said terrets fitting upon the upper strip r . The elasticity of the side, m' , admits of the terrets and screws being set firmly to their places; whereas, when a rigid wooden or metal surface is used in place of thick leather, they are liable to become loose when the screw-thread becomes worn. The pad d is also made in one piece, extending from end to end of the iron, its centre preventing the back of the animal from contact with the burr e of the terret A . The pad-frame is usually made of malleable iron, cast or stamped, or it may be made of brass, though the former metal is preferable. The flanged edges are plated, and thus made to present an ornamental appearance.

The advantages of this improved article of manufacture consist in simplicity and durability, but more particularly in the facility and dispatch with which harness-pads so made can be produced, thereby enabling them to be furnished at a much cheaper rate than those now in use.

I claim as new, and desire to secure by Letters Patent—

As an improved article of manufacture, a harness-pad and iron, constructed as described, consisting of the solid flanged iron m , having the crupper-loop cast upon and with it, and the continuous pad d , with its upper surface, m' , formed of sole-leather, covering and receiving the burrs e , as herein described, for the purpose specified.

HEBER R. RIDGLEY.
